CONVERTIBLE ARTICLE OF FURNITURE

Howard N. Barnum, South Euclid, Ohio

Application August 11, 1943, Serial No. 498,177

3 Claims. (Cl. 155—43)

1

This invention relates to furniture of the convertible and/or "knock-down" class, and more particularly to a piece of furniture for use in game or recreation rooms which, when in one position, serves as a seat or bench and, when in another position, provides a ping pong table or a table on which other games may be played or which may be used for general purposes.

An object of the invention is to provide a piece of furniture of the convertible class that serves both of two purposes efficiently and satisfactorily, and that is sturdy and has an attractive appearance and stands solidly when in either of the two positions in which it is intended for use.

Another object of the invention is to provide a piece of furniture of the so-called "knock-down" variety which may be packed in small compass for shipment and storage and readily assembled for use.

A further object is to provide a piece of convertible furniture wherein very few, if any, of its parts have to be adjusted in adapting the structure to its alternate purposes, and which has a rocking or rolling contact with the floor, when being converted, which action serves to shift the structure between a position near a wall, where it desirably stands when used as a seat or bench, and a position in properly spaced relation to said wall, when the structure is to be used as a table.

Objects of a more detailed nature will appear as this description proceeds, reference being had to the accompanying drawing in which Fig. 1 is a perspective view of a piece of furniture incorporating the invention and showing it in the position it occupies when used as a seat or bench, and Fig. 2 is a vertical section through the same, substantially on the line 2—2 of Fig. 1, the view including, in dotted lines, the structure in the position it occupies when used as a game or other table.

In the drawing, wherein like reference characters designate corresponding parts in the two views, 1 is a rectangular panel that constitutes the back of the bench or seat when the structure occupies one of its two intended positions, and that forms the table top when the structure is in the other of such positions. The panel 1 is desirably made in two parts or sections designated 1^a and 1^b, respectively, that are of substantially equal size and nearly square. Attached to one side of the panel are stringers 2 and 3, each being disposed parallel to and near one of the lateral edges of the panel. These stringers are desirably detachably connected to the panel, as by being apertured at suitable intervals and engaged over

2

hooks 4 that project from the panel. The stringer 2 is narrow, relative to the stringer 3, the latter being of sufficient width to constitute the bottom of a compartment 5, other walls of which are formed by a portion of the panel 1 and by a front board 6. A seat 7 provides a lid for the compartment 5, and adjacent its forward edge is supported by the front board 6 and at its rear edge by two cleats 8 that are carried, respectively, by the parts 1^a and 1^b of the panel. The front board 6 and stringers 2 and 3 are provided with end extensions or tenons 6^a, 2^a and 3^a, respectively, the tenons 6^a having slots for the reception of wedges 9, while the tenons 2^a and 3^a may be apertured for tapered pegs 10, if desired.

12, 12 are end members that are provided with mortises for the reception of the tenons 2^a, 3^a and 6^a, and also with apertures in which are journaled trunnions 7^a of the seat 7. When the 15 stringers are attached to the panel 1 and the end members 12 applied to the tenons thereof, and with the tenons 6^a of the front board 6 engaged through the mortises provided for them, the structure will be in a properly assembled condition, 20 and the parts may be firmly held in their respective positions by wedges 9 (and pegs 10 if the latter are included) when they are forced as far as they will go into the respective openings provided therefor.

Each end member 12 incorporates a relatively wide portion 13, an edge 15 whereof, that is parallel to the panel 1, is spaced from said panel a distance that may be termed "table height." Obviously, this distance is variable, depending upon the purpose to which the table is to be put. An edge 16, that is at right angles to the edge 15, is desirably flush with one of the lateral edges of the panel 1. Connecting the edges 15 and 16 is a rocker portion 17. In other respects the members 12 may be shaped as desired, each, in the present case, having the more or less conventional profile of a Pullman bench end. Pivotally connected to the inner side of each member 12, desirably in the angle between the stringer 2 and the adjacent portion of the panel 1, is a leg 20. The legs 20 are intended to be folded against the panel 1 when the structure occupies the position shown in Fig. 1, and in full lines in Fig. 2. In such position, the structure serves the purpose 25 of a seat or bench which may be placed with the panel 1 practically against the wall of a room, such as a game or recreation room. Various articles may be accommodated by the compartment 5, to which access is readily gained by 30 swinging the seat 7 upwardly on its trunnions 35

^{7a}, such articles, for example, as pillows or cushions for the seat, and ping pong racquets, balls, nets and/or other game apparatus.

When it is desired to convert the piece of furniture from a seat or bench to a table, the paraphernalia for playing the game may be removed from the compartment 5 and the legs 20 may be thrown out into right angular relation to the panel 1, being stopped in such position by the stringer 2, and the structure rolled over on the rocker portions 17 so that it stands on the edges 15 and on the legs 20, as indicated in dotted lines in Fig. 2. This process of conversion may be reduced to nothing more than the rocking of the structure from one position to the other, simply by making the pivotal connections between the end members 12 and the legs 20 sufficiently loose to permit the legs to swing under the influence of gravity. The rocking over of the structure from the position it occupies near the wall as a bench or seat, to the position it occupies as a table, spaces the structure a sufficient distance from the wall to permit its use as a ping pong or other table without further shifting; and furthermore, the shaping of the end members to provide the rocker portions 17 provides the highly essential toe room for persons having occasion to closely approach the table.

When the structure is disassembled, the parts may be compactly arranged by reversing the end members with respect to each other and placing them flatwise between the sections 1^a and 1^b of the panel 1, in which condition they and the panel sections may be wrapped, or placed in a carton of corrugated paper or other material. The stringers 2 and 3, front board 6 and seat 7 may also be compactly arranged for wrapping, or for insertion in a long carton. The small parts, consisting only of the wedges 9 and pegs 10, may be enclosed in an envelope or the like and packed in one of the aforementioned wrappings or cartons.

Having thus described my invention, what I claim is:

1. An article of furniture of the convertible class comprising a panel and two end members, one such member attached to the panel adjacent each end thereof, each end member having a floor engaging part so spaced from the plane of the panel that when said part is in contact with the floor the panel is located table-height from the floor, and a second floor engaging part in substantially the plane of one of the lateral edges of the panel, and a permanently exposed rocker portion of considerable radius between said parts that is adapted to have direct rolling contact with the floor, and a seat situated between said end members with its rear edge adjacent said panel and its front edge spaced from said panel a distance within the spacing from said panel of the adjacent ends of the rocker portions of the end members whereby to avoid any tendency of the article to rock under the influence of weight imposed upon the seat when the second floor engaging parts of the end members bear upon the floor.

2. An article of furniture of the convertible class comprising a panel and two end members, one such member attached to the panel adjacent each end thereof, each end member having a floor engaging part so spaced from the plane of the panel that when said part is in contact with the floor the panel is located table-height from the floor, and a second floor engaging part in substantially the plane of one of the lateral edges of the panel, and a permanently exposed rocker portion of considerable radius between said parts that is adapted to have direct rolling contact with the floor, a seat situated between said end members with its rear edge adjacent said panel and its front edge spaced from said panel a distance within the spacing from said panel of the adjacent ends of the rocker portions of the end members whereby to avoid any tendency of the article to rock under the influence of weight imposed upon the seat when the second floor engaging parts of the end members bear upon the floor, and means for maintaining the panel substantially parallel with the floor when the first mentioned floor engaging parts of the end members are in contact with the floor, said means comprising an element pivoted to the structure and a stringer extending along the other lateral edge of the panel and adjacent which said element is pivoted and which stringer serves as a stop for the element to limit the swinging movement thereof in a direction away from the panel to substantially 90°.
3. An article of furniture of the convertible class comprising a panel and two end members, one such member attached to the panel adjacent each end thereof, each end member having a floor engaging part so spaced from the plane of the panel that when said part is in contact with the floor the panel is located table-height from the floor, and a second floor engaging part in substantially the plane of one of the lateral edges of the panel, and a permanently exposed rocker portion of considerable radius between said parts that is adapted to have direct rolling contact with the floor, a seat situated between said end members with its rear edge adjacent said panel and its front edge spaced from said panel a distance within the spacing from said panel of the adjacent ends of the rocker portions of the end members whereby to avoid any tendency of the article to rock under the influence of weight imposed upon the seat when the second floor engaging parts of the end members bear upon the floor, and means for maintaining the panel substantially parallel with the floor when the first mentioned floor engaging parts of the end members are in contact with the floor, said means comprising a stringer extending along the other lateral edge of the panel, and two legs, each pivotally connected to one of the end members on an axis at right angles thereto so as to swing in a plane parallel to that of said member between an ineffective position closely adjacent the panel and an effective position in which it is stopped by engagement with said stringer.

HOWARD N. BARNUM.
